UNITED STATES PATENT OFFICE.

JOSEPH NUMA MAINGOT, OF TRINIDAD, BRITISH WEST INDIES.

DESK UTENSIL.

No. 823,798.

Specification of Letters Patent.

Patented June 19, 1906.

Application filed October 3, 1905. Serial No. 281,163.

To all whom it may concern:

Be it known that I, JOSEPH NUMA MAINGOT, of Trinidad, British West Indies, have invented a new and Improved Desk Utensil, of which the following is a full, clear, and exact description.

This invention relates to an article that can be used to moisten envelops or stamps or for the purpose of moistening the fingers when counting paper money or sheets, that can be used to stamp an envelop or postage stamp and at the same time blot up or absorb the surplus moisture, and the device also embodies a cup in one end that can be used for mucilage or gum and on the other end embodies a receptacle for water that can be used to moisten an absorbent pad, the flow of the water being regulated and being adapted to be entirely cut off.

Reference is to be had to the accompanying drawings, forming a part of this specification, in which similar figures of reference indicate corresponding parts in all the views.

Figure 1 is a perspective view of the device on a suitable stand with the blotting-pad swung back so as to uncover the absorbent pad. Fig. 2 is a section showing the stamping-pad in full lines in its operative position. Fig. 3 is a section on line 3-3 of Fig. 2. Fig. 4 is a side view of a modified form of device on a suitable stand. Fig. 5 is a longitudinal section of the same. Fig. 6 is a section on line 6-6 in Fig. 5; and Fig. 7 is a similar view, but showing the feed from the water-receptacle to the absorbent pad cut off.

The tubular body 10 is divided at a suitable point into two compartments 11 and 12, and these compartments are joined by a screw-thread 13. The upper compartment is designed to form a receptacle for mucilage or paste and has the closure 14 provided with a suitable brush 15, and a wiping-ring 16 is conveniently arranged to take off surplus mucilage from the brush when it is withdrawn. The lower receptacle 12 is designed to contain water and has rotatably arranged at its bottom a disk 17, arranged to revolve and bear against a stationary disk 18, these disks 17 and 18 having holes 19 and 20, respectively, the rotation of the disk 17 throwing the holes in and out of register, and a pin 21, working in a slot 22 on the disk 17, limits the movement, so as to indicate when the feed is shut or when it is open. A post 23, extending up through the disk 18, with the nut 24 and the spring 25 insure a close con-

tact between the disks 17 and 18. A holder 26 is hinged at 27 and can be held up by a suitable spring 28 to maintain a sponge or other proper absorbent pad 29.

Pivoted on either side of the tube 10 are a pair of arms 30, which hold a plate 31, on the face of and over the two ends of which can be arranged a blotting-strip 32, and spring-actuated holders 33 project out on either side of a central pin 34, being actuated by the spring 35, which is coiled around the pin 34, these spring-actuated clamps extending across the end of the structure, as at 36, and being provided with a suitable handle 37. The ends of the arms 30 are bent to form finger-pieces 30^a, and when the device is held as in Fig. 2 the finger-pieces 30^a can be operated to throw the blotting-pad 32 out of the way, as shown in dotted outline, and the sponge can be used to moisten the gum on envelops or the face of an envelop for the affixing of a stamp, and then the finger-piece 30^a can be again released and used to put pressure on the part to be affixed, at the same time absorbing any surplus moisture that may be on the articles. When the device is thus used, hooks 38 act to limit the movement of the arms 30 and steady the blotting device. The water from the receptacle can be fed through the holes 19 and 20 by placing them in register and can be as quickly shut off by a simple turning of the flange 17 to bring the holes out of register.

As shown in Fig. 1, the article can be placed horizontally on the standards 39 of a suitable block 40 and is handy for the purpose of moistening the thumb when counting sheets of paper or money or turning the leaves of a book.

In Fig. 4 and in subsequent figures I show a modification in which the tube is arranged as in the previous structure, and the water-receptacle feeds the absorbent pad in the same way; but on the end of the stopper 14^a of the mucilage-receptacle I arrange a plate 41, over which the blotting material 42 can be stretched, and on either side of either end of the plates a bearing-strip 43, in which is arranged to rotate a shaft 44, carrying a cam 45 and having on one end of each an operating-knob 46. It will be seen that by turning the knobs one way the blotting material 42 can be tightly clamped on the plate 41, and by a reverse turning of the knobs the blotting-paper can be released to be replaced by a fresh one.

In the manipulation of this device it will be used the same as the previous construction with the exception that by simply turning over the tube after moistening an article 5 the blotting-pad is at hand ready for use. The blotting-pad also serves the purpose of holding down a stamp after it has been placed on the moistened surface, the edge of the blotting-pad being on the line of perforation 10 of the stamp, and thus serving as a holder when a stamp is torn from its strip. Of course it will be evident that I have not enumerated all the uses to which this device 15 might be put; but I have mentioned a number of them, so as to indicate the general uses of it.

Having thus fully described my invention, I claim as new and desire to secure by Letters Patent—

- 20 1. An article of the kind described comprising a tubular casing forming a handle, said casing having two compartments at the ends thereof and being separable at a point below the upper compartment, an absorbent 25 pad at the end of one compartment, and means as the perforated spring-pressed disks adapted to turn in relation to each other for regulating the flow to said pad.
2. An article of the kind described, comprising a tubular casing divided into two compartments one adapted to contain mucilage and the other water, an absorbent pad at the end of the water-compartment, and means as the perforated spring-pressed disks 30 35 adapted to turn in relation to each other for regulating the flow of water to the pad.

3. The combination with the casing having a water-compartment, and the absorbent pad supplied from the water-compartment, of the frame supported on the casing and 40 adapted to swing beneath the absorbent pad, said frame having means for supporting a blotter thereon.

4. The combination with the tubular casing having the water-compartment and 45 means for regulating the flow of water from the end of the compartment, of a swinging pad-holder supported at the end of the compartment, means for securing the pad-holder in place, and an absorbent pad in the pad- 50 holder.

5. The combination with the tubular casing having a water-compartment in the end thereof, of the absorbent pad at the end of the water-compartment, the swinging blotter-holder to move opposite the pad, said blotter-holder having means for carrying a blotter thereon, and arms pivoted on the casing and secured to the blotter-holder. 55

6. The combination with the tubular casing having a water-compartment with a perforated bottom therein, of a perforated disk held opposite the bottom of the water-compartment, spring-pressed means for holding the disk snug against the said bottom, and an 60 absorbent pad held against the said perforated disk. 65
